UNITED STATES PATENT OFFICE.

SAMUEL A. WHITNEY, OF BOSTON, MASSACHUSETTS, AND CHARLES J. YOST, OF WENONAH, NEW JERSEY, ASSIGNEES TO WHITNEY GLASS WORKS, A CORPORATION OF NEW JERSEY.

DESIGN FOR AN AMMONIA-BOTTLE.

45,248.

Specification for Design.

Patented Feb. 10, 1914.

Application filed November 13, 1912. Serial No. 731,183. Term of patent 14 years.

To all whom it may concern:

Be it known that we, SAMUEL A. WHITNEY, residing at Boston, county of Suffolk, State of Massachusetts, and CHARLES J. YOST, residing at Wenonah, county of Gloucester, State of New Jersey, both citizens of the United States, have invented a new, original, and ornamental Design for an Ammonia-Bottle, of which the following is a specification, reference being had to the accompanying drawing, forming part thereof.

The figure is a side elevation of an ammonia bottle showing our new design in which 1 designates the body of the bottle, and 2 designates the neck thereof. The neck is exteriorly of the form of a truncated cone 3 at the bottom, an inverted truncated

cone 4, at the top, and a cylindrical band 5, intermediate of said cones adjoining the narrow diameters thereof.

We claim:—

The ornamental design for an ammonia bottle, as shown and described.
